UNITED STATES PATENT OFFICE.

ANTOINE JOURDANET, PIERRE BILLET, AND FERDINAND BARON, OF LYON, FRANCE.

CARBURETER.

No. 891,936.

Specification of Letters Patent.

Patented June 30, 1908.

Application filed June 17, 1907. Serial No. 379,428.

To all whom it may concern:

Be it known that we, ANTOINE JOURDANET, PIERRE BILLET, and FERDINAND BARON, citizens of the French Republic, residing at Lyon, in France, have invented a certain new and useful Carbureter, of which the following is a specification.

This invention relates to carbureters for mixing vaporizable petroleum spirit or the like with air for the alimentation of explosion engines.

The carbureter which forms the object of the present invention is shown in vertical section in the annexed drawing.

15 A is a crown or cap screw-threaded at A¹ forming a tubular connection and its flange A² is internally screw-threaded to engage similar threads on a cylinder B in which is formed a valve seat B¹ closed by a valve C.

20 The stem C¹ of the latter is guided in, its movements by a guide D carried by a perforated spider D¹ mounted on a shoulder B² in the cylinder B and forming one member of a throttle the other member of which is formed

25 by a perforated disk Y having a flange Y¹ rotatably mounted in the upper part of the cylinder B and operatable by a projecting arm X passed through a slot B³ in the cylinder B. The tubular downward prolongation B⁴ of

30 the cylinder B is internally screw-threaded at B⁵ to engage threads on the hollow cylinder J within which a hollow cylinder E slides forming means for automatically controlling an additional supply of air. The cylinder E is

35 pierced with openings E¹, preferably having the shape of triangles of which the base is at the top and its base E² is formed with openings E³. The cylinder J is also pierced with openings J¹. A jacket F has its upper edge

40 bent inwardly at F¹ to engage over a flange B⁶ of the cylinder B. The jacket F extends downwardly inclosing a space surrounding the cylinder J, and is shouldered outwardly at F² and at its lower end it is carried out-

45 wardly at F³ and downwardly at F⁴, and is bolted by bolts Q and nuts U to the flange G² of a second jacket G pierced with holes G¹ for the passage of air, and forming in its lower part the float chamber of the carbureter.

50 Between the flanges F³ G² are two plates H, O the lower plate having a central orifice O¹ and the upper plate being perforated at H¹ and H² to form the fixed member of an adjustable throttle of which the movable portion consists of a cylindrically flanged perforated plate I rotatably mounted in the jacket

F below the shoulder F² and provided with an arm I¹ extending through a slot F⁵ in the jacket F.

The passage of carbureted air is regulated 60 by the throttle formed by the plates H, and I, of which the position is regulated from outside by means of the arm I¹.

Between the flange F⁴ of jacket F and the air holes G¹ of jacket G is arranged a supplementary envelop K brazed to the lower jacket and forming an annular passage for the air.

The jacket G is shouldered at G²⁰ below the air holes G¹; and again at G³ and its base narrows to a conical flange G⁴ in which is fitted the body V¹ in which the valve seat V² is formed against which the valve V bears upwardly. The stem V³ of valve V carries the float P which is preferably of cork. On the 70 shoulder G²⁰ is closely fitted a plate G⁵ having a central orifice G⁶ for passage of the valve stem V³. On the plate G⁵ is supported a plate G⁷ which is flared conically at G⁸ and thence carried horizontally outward at G⁹. 75 G¹⁰ are air holes in part G⁸. The supply of essence to the carburization chamber is effected by capillarity, by means of short rods of ratan N carried by tubes M passing from orifices in plate G⁵ to orifices in plate G⁷.

The jacket G is internally lined with a cylindrical piece of felt U¹ which conducts the spirit to the ratan rods N by which the spirit is conveyed by capillarity to the annular felt plate Z. Above the plate Z is a felt 80 plate L perforated at L¹ and perforated plate W of metal. The valve C is normally held on its seat by a spring S, and the spring valve E is normally pressed downwards by a spring R surrounding a fixed stem T.

85 F⁶ are air holes in jacket F.

It will be seen that the suction of the engine which is connected to cap A draws air in at holes G¹ G¹⁰ into the space above plate G⁵. It passes through the felt plate L which 90 is kept down in place by the metal plate W and takes up the spirit supplied to said plate by the ring Z to which the spirit has been supplied by capillarity through the numerous capillary passages in the ratan N supplied by the felt G which is immersed in the spirit in the float chamber.

The shape of plate O prevents direct current of air acting on the felt ring Z. Additional air enters by the holes F⁶ and H¹. The 100 carburized air passes up through holes H² and E³, lifts valve C and passes through the

holes in the plates D¹. By closing the throttle I the maximum richness of carburization is given; by opening it the quantity of spirit and consequently the richness of carburization, are reduced; at low speed the valve E is barely lifted and admits at E¹ only the additional air required for normal carburization for low speed. On advancing the ignition the aspirations become more forcible and tend to increase the quantity of spirit sucked in, but at the same time the valve E rises more and allows a greater quantity of pure air to pass, so that the mixture may be either automatically re-established as at low speed, or diminished in richness according to the setting of spring R.

The arm X of the throttle Y is intended to be permanently fixed according to the power of the motor to be actuated.

20 What we claim as our invention and desire to secure by Letters Patent of the United States is:—

1. In a carbureter the combination with a carbureting chamber and a spirit supply chamber, of pieces of ratan for conducting

the spirit from the latter to the former by capillary action, and a felt supplier in contact with the ratan in the spirit supply chamber.

2. In a carbureter the combination of a 30 valve body, a suction valve therein, a throttle above the suction valve, a spring controlled extra air inlet valve below the suction valve, a mixture chamber with uncontrolled air inlets below the extra air inlet 35 valve, a float chamber below the mixture chamber, and a throttle between the mixture chamber and extra air inlet valve operative to control the passage between said mixture chamber and suction valve and also to control additional air inlets to the mixture chamber. 40

In witness whereof we have signed this specification in the presence of two witnesses.
